(57) **CLAIM**

The ornamental design for a cord stopper, as shown and described.

DESCRIPTION

FIG. 1 is a top front right perspective showing the cord stopper in use.

FIG. 2 is a top front right perspective of the cord stopper of FIG. 1.

FIG. 3 is a right side elevation of the cord stopper of FIG. 1.

FIG. 4 is a left side elevation of the cord stopper of FIG. 1.

FIG. 5 is a rear elevation of the cord stopper of FIG. 1.

FIG. 6 is a front elevation of the cord stopper of FIG. 1.

FIG. 7 is a top plan view of the cord stopper of FIG. 1; and, FIG. 8 is a bottom plan view of the cord stopper of FIG. 1. The broken lines shown in the drawings are for environmental purposes only and form no part of the claimed design.
